Mitchee & Allyn

UNITED STATES PATENT OFFICE.

HERBERT J. Gwyer, of Yonkers, New York.

CORNER CONNECTION FOR CABINETS.

1,343,209.

Specification of Letters Patent. Patented June 15, 1920.

Application filed December 2, 1919. Serial No. 341,916.

To all whom it may concern:

Be it known that I, HERBERT J. Gwyer, a citizen of the United States of America, residing at Yonkers, Westchester county, New York, have invented a new and useful Corner Connection for Cabinets, of which the following is a specification.

My invention relates to novel corner fastening means for frames such as provided around the edges of panels. In such constructions, it is important that the corners of the frames should be very securely and permanently connected, because frequently, when such frames are used in the construction of heavy cabinets, the same are subjected to severe twisting strains which would tend to open the corners. The invention has particular utility when employed in top and bottom panel frames used for refrigerator casings such as disclosed in my co-pending application, Serial No. 303,197, which latter is illustrative of a knock-down refrigerator cabinet. In the present as well as in the former case, it is contemplated that the top and bottom panels are to be screwed or bolted to adjacent side panels, and my present improvement provides not only connecting means for the corners of the top and bottom panels, but it also provides protected passages through said corners for the purpose of receiving the fastening screws or bolts, thereby making it unnecessary to form separate passages and to provide additional protecting means for the same. From the foregoing, it will be apparent that the objects of my invention include simplicity of construction, economy, strength, and durability.

In the drawings, Figure 1 is a plan view 40 of a corner of a frame equipped with my invention.

Fig. 2 is a view of the underside thereof.

Fig. 3 is a section on the line 3-3 of Fig. 2.

Figs. 4 and 5 are perspective views of details.

1-2 represent the two ends of two panel framing pieces which are mitered so as to come together at the proper angle. In the 50 particular construction shown, the undersides of the framing pieces are longitudinally grooved to receive the edges of the side box panels of a cabinet or box. At the meeting line of the mitered ends of the 55 pieces 1 and 2 is formed a hole or passage.

3 represents a locking piece for the top side of the framing pieces, the same being preferably in the form of an annular washer centrally countersunk, and provided around its outer edge with a depending flange, the 60 lower edge of which is preferably provided with spurs 4-4. This locking piece is driven into the material of the framing pieces 1 and 2 in such a position as to partially overlap each piece and so that the hole 65 in the locking piece will be concentric with the passage through the mitered corners. 5 is a complementary locking piece which is preferably angular in outline so as to fit into the grooved underside of the framing 70 pieces 1 and 2 in the manner shown in Fig. 2. This second piece is likewise preferably provided with a flange around its edge which may also have spurs 6-6. The second locking piece 5 also has a hole which 75 registers with the bore through the framing pieces. The second locking piece 5 is likewise driven into the wood of the framing pieces so as to become interlocked therewith. It will be seen that the locking piece 5 not 80 only holds the members 1 and 2 together by reason of the fact that the edge thereof is driven into the material of both of said members, but its design is such that it acts as an angular key when seated in the bottom 85 of the angular grooved portion at the underside of the corners of the frame.

Both of the locking pieces 3 and 5 may be economically produced from sheet metal.

Added security may be had by providing 90 means to tie the locking pieces together, which means is preferably in the form of a tube 7, which may be passed through the holes in the locking pieces 3-5 and through the passage in the frame, the ends of the 95 said tube being upset outside of the members 3 and 5 so as to rigidly connect said two locking pieces. This tube 7 not only acts to tie the locking pieces together, but it also serves as a means to protect the passage through the frame and as a guide-way 100 for the fastening screw and bolt, the latter being designated at 8 in Fig. 3.

When a cabinet or box is constructed with bottom and top panels having corners constructed in the manner illustrated in the accompanying drawings (the said top and bottom panels being spaced by the usual side panels), a fastening means 8 in the form of a bolt may be passed entirely 110

through the assembled structure at each corner so as to tie together the top and bottom panels in a most effective manner.

What I claim is:—

- 5 1. In a frame of the character described, two framing pieces meeting at an angle, means for connecting said framing pieces at the meeting line comprising two complementary metallic locking pieces arranged 30
- 10 on the top and bottom of the frame and each partially overlapping each of said framing pieces at the meeting angle, each locking piece having a hole therein, a passage through the corner of the frame at 35
- 15 the meeting line registering with said holes in the locking pieces, with means on each of said locking pieces to be driven into the material of said framing pieces to secure the parts together, and a tube passing through 40
- 20 said locking pieces and upset outside of the same.
- 25 2. A structure such as described in claim 1, the locking piece on the underside of the frame being of an angular outline.
3. In a frame for box panels or the like,

two framing pieces meeting at an angle, a passage extending through said framing pieces at the meeting line, two complementary metallic locking pieces each having a hole therethrough, arranged to register 30 with said passage through the frame and located respectively on the top and bottom of said frame, spurs on each of said locking pieces, said spurs penetrating into the material of said framing pieces, the top locking piece being countersunk, a metallic tube forming a lining for the passage through said framing pieces and upset outside of 35 said locking pieces to tie the same together and to form a guide passage for a bolt or 40 screw.

4. A frame construction such as described in claim 3, the underside of said framing pieces being grooved, said grooves meeting at an angle, the locking piece at the underside being of angular outline and fitting 45 into the said grooved portions at said corner.

HERBERT J. GWYER.
